MOLDED PULP BOTTLE PACK

Ernest L. Shepard, Fairfield, Maine, assignor to Keyes
Fibre Company, Portland, Maine, a corporation of Maine

Application January 23, 1957, Serial No. 44,563

Term of patent 14 years

(Cl. D58—26)

Fig. 1 is a side elevational view of a molded pulp bottle pack embodying my new design; and

Fig. 2 is a top plan view of the bottle pack of Fig. 1.

The side of the bottle pack not shown is substantially the same as the side shown.

The broken line showing of the bottle is for illustrative purposes only.

What is claimed:

The ornamental design for a molded pulp bottle pack, as shown and described.
